UNITED STATES PATENT OFFICE.

FRANK HUDDLESTON, OF RADISSON, WISCONSIN.

WALL-PAPER-HANGING APPARATUS.

1,192,637.

Specification of Letters Patent. Patented July 25, 1916.

Application filed October 26, 1915. Serial No. 58,003.

To all whom it may concern:

Be it known that I, FRANK HUDDLESTON, a citizen of the United States, residing at Radisson, in the county of Sawyer and State of Wisconsin, have invented new and useful Improvements in Wall-Paper-Hanging Apparatus, of which the following is a specification.

The present invention relates to improvements in apparatus for applying paper to a wall or ceiling.

In carrying out my invention it is my purpose to provide a simple, cheap and easily operated device whereby paper may be wound upon a roller, paste applied to the paper and the paper applied upon a wall or ceiling with the least amount of physical exertion and without necessitating the service of a skilled artisan.

A further object of the invention is to provide a machine or apparatus including a roller upon which the paper is wound, a paste receptacle having a brush attached thereto and means associated with the receptacle whereby a certain and desired amount of paste may be delivered to the paper upon the roller; said delivering means being in the nature of a fluid, such as compressed air deposited in a receptacle arranged upon the device, and means being provided for regulating the pressure of said air.

Another object of the invention is to provide a device of this character whereby the paper may be properly pasted upon a wall or ceiling at the corners thereof.

With the above and other objects in view, the improvement resides in the construction, combination and arrangement of parts set forth in the following specification and falling within the scope of the appended claims.

In the drawings: Figure 1 is a perspective view illustrating the device in operative position, Fig. 2 is a front elevation, parts being broken away and parts being shown in section, Fig. 3 is a central vertical transverse sectional view through Fig. 2, Fig. 4 is a detail front elevation with one of the roller supporting arms removed, and Fig. 5 is a similar elevation showing the crank connected with the roller.

In the drawings the numeral 1 designates a suitable pawl or handle which has secured thereon adjacent one of its ends a tank 2, the said tank being provided with a valved inlet 3 whereby air or other fluid may be forced within the said tank at a desired

pressure. Secured upon the handle 1 and leading from the said tank 2 are angularly arranged pipe members 4-4, said angular members being provided with a connecting member 5 so that the said pipes 4 and 5 are substantially V-shaped in elevation.

Secured centrally to the end of the tank 2 is a substantially U-shaped pipe member, the arms 4-4 of which being connected by and communicating with a pipe member 5. Extending from the pipe 5 are a plurality of short pipes 7 which provide outlets for the pipe 5 and for the pipe sections 4. Snugly fitted within the pipe 5 is a tube 8 that is provided with a plurality of openings 9, which when the tube 8 is rotated within the pipe 5, to one position, are adapted to register with the short pipes 7. The branch pipes 4 beyond the connecting pipe 5 are provided with solid extensions, and the numeral 10 designates a brush which may rest upon shoulders provided by the said extensions and which has its head formed with openings through which pass the short pipes 7. The solid extension upon one of the branch pipes is projected a greater length than the other and is provided with an opening forming a bearing for a trunnion 10 of a roller 12. The opposite end of the roller is formed with a substantially frusto-conical concavity 13, the same receiving a frusto-conical member 14 provided upon one end of the removable member 15, the said removable member receiving one of the ends of an arm 16, the second end of the arm being reduced, as at 17, and being received within a slot or bore provided upon the solid extension 18 of the second arm or pipe member 4. A screw 19 passes through the said bore 18 and engages with the member 17 to normally sustain the member 16. The members 15 and 16, of course, project a suitable distance beyond the end of the roller, but when the device is employed for pasting paper upon the corner of a room, the said members 15 and 16 may be removed so that the said members will not interfere with the operation of the device in the corners of a room.

The member 15 is in the nature of a threaded element and is received in a threaded aperture in the member 13. The threaded member is, of course, removable and the threaded aperture in the member 14 may receive the threaded end of a crank handle 20 which is adapted to force the member 14 into contact with the wall of the

concavity 13 and which when rotated, will wind the paper upon the roller 12.

Pivots secured to the handle or staff 1 is a lever 21, the said lever being normally swung in one direction through the medium of a spring 22, while the numeral 23 designates a rod which is connected with an offset portion or arm 24 arranged upon the member 8. The spring 22 is normally 10 adapted to rotate the member 8 to bring the perforations of the same out of register with the pipe members 7, but upon actuating the said lever it will be noted that the perforations 9 of the said member 8 will 15 align with the pipes 7 so that air will be delivered from the tank 2 and the paste within a paste box 25 arranged between the arms 4—4 will be forced therefrom through the said pipes and between the bristles of 20 the brush and thus be readily applied to the paper roller 21.

If desired, a pipe section 26 may communicate with the air receptacle 2, the said pipe 26 having offset ends 27—27 which are 25 arranged within the pipe sections 4—4 and the paste receptacle 25 may be provided with a central opening 28 arranged centrally between the pipe members 27—27. The paste will naturally gravitate through 30 the opening 28 to the central portion of the connected pipe members 4—4. As air is normally forced through the pipe 26 and the oppositely arranged ends or arms 27—27 thereof, the said paste will be forced 35 through the angular members 4 and therefrom to the connecting member 5 and will find an exit through the opening 9 in the member 8 to deposit a certain amount of paste from the tubes 7 to the brush 9.

40 From the above description, taken in connection with the accompanying drawings, the simplicity of the device, as well as the advantages thereof will, it is thought, be perfectly apparent to those skilled in 45 the art to which such invention appertains without further detailed description.

Having thus described the invention, what I claim is:

1. In a paper hanging apparatus, a roller 50 upon which the paper is wound, a receptacle containing paste arranged below the

roller, a brush connected with the receptacle, a compressed air tank communicating with the paste receptacle, and means for admitting air from the tank to the receptacle for ejecting paste therefrom to the brush. 55

2. In a paper hanging apparatus, a roller upon which the paper is wound, a receptacle containing paste arranged below the 60 roller, a brush connected with the receptacle, a compressed air tank communicating with the receptacle, means for admitting air from the tank to the receptacle for ejecting paste therefrom to the brush, and 65 mechanism for regulating said means.

3. In a wall paper pasting apparatus, a staff, an air tank containing compressed fluid connected with the staff, a receptacle containing paste, a pipe leading from the 70 air tank and communicating with the receptacle, a regulating valve for the air tank, a brush connected with the receptacle, a plurality of tubes arranged between the receptacle and the brush, a valve member between the tubes and the receptacle, means for actuating the said valve member to open the receptacle to the tube, and a roller trunnioned upon the staff opposite the 75 brush.

4. In a device for the purpose set forth, a staff, a tank containing a compressed fluid secured thereon, a receptacle containing paste arranged above the fluid tank, a pipe member communicating with the fluid tank and surrounding the paste receptacle 80 and having solid extensions, a brush member secured to the said extensions, tubular members between the brush member and the said pipe member, a tubular valve in the 85 pipe member having perforations communicating with the tubes, means connected with the staff for actuating the valve, and a roller journaled in bearings in the solid extensions of the pipe disposed above and 90 in contacting relation with the brush. 95

In testimony whereof I affix my signature in presence of two witnesses.

FRANK HUDDLESTON.
